Patented Aug. 17, 1926.

UNITED STATES PATENT OFFICE.

JEAN MARTIAL LOBIT, OF BROOKLYN, NEW YORK.

DOWN SPOUT.

Application filed November 15, 1921. Serial No. 515,209.

This invention relates to down spouts and has for one of its objects to provide a spout or conduit in which liquid will flow freely and without escape as long as the spout is open but which will permit the escape of liquid at any one of a plurality of points, spaced longitudinally of the pipe or spout, when the pipe is clogged below that particular point.

Another object is to provide a down spout having the characteristics above set forth and which is made of similar sections.

A further object is to provide a down spout having the characteristics above set forth and which may be readily assembled and disassembled.

Other objects and advantages will appear as the invention is hereinafter disclosed.

Referring to the drawings which illustrate what I now believe to be preferred forms of the invention,

Fig. 1 is an elevation illustrating one embodiment of my invention employed as a rain spout.

Fig. 2 is a detail elevation, partly in section, of adjacent ends of two of the pipe sections shown in Fig. 1.

Fig. 3 is a detail side elevation of the structure shown in Fig. 2.

Fig. 4 is a section taken on the line 4—4 of Fig. 1.

Fig. 5 is a view similar to Fig. 2 but illustrating a modification.

While my down spout is adaptable to a variety of uses it possesses marked advantages when employed as a rain spout or pipe, and I have therefore so illustrated it. In the embodiment shown in Figs. 1 to 4 the spout consists of a plurality of pipe sections 10, 11, 12, 13, 14, and 15, which are serially connected in the sense that each section, save the lowest one, discharges into the section below it. Preferably, each of said pipe sections, save possibly the uppermost section 10 and lowermost section 15, is identical to any other section, thereby minimizing the number of stock parts and facilitating replacements and assembly. Each of the sections 10 to 15 is shown of

uniform cross section, in the present illustration cylindrical, throughout the greater portion of its length. Each of the sections 10, 11, 12, 13 and 14 is shown provided with a reduced portion 16 (see particularly Fig. 2) at its lower end, the exterior diameter of such portions 16 being

sufficiently smaller than the upper ends of the sections 11, 12, 13, 14 and 15 to provide a substantial clearance opening 17 at each junction. It will be noted that each section 10, 11, 12, 13 and 14 extends a substantial distance into the corresponding section immediately below it. Means are preferably provided for spacing the lower end of each of the sections 10 to 14 from the inner wall of the section into which it extends and for detachably connecting the sections one to another. One form of such means is illustrated in Figs. 1 to 3 and may be constructed substantially as follows.

A plurality of pins 18, two in the present illustration, are riveted or otherwise secured to the lower end 16 of each of the sections 10 to 14. These pins 18 project laterally from the end portions 16 to which they are secured and are adapted to seat in corresponding notches 19 provided in the upper ends of the sections 11 to 15. Spacing collars 20 are secured, one upon each of the pins 18 between the walls of adjoining pipe sections, leaving the clearance openings 17 substantially unimpeded save for the slight obstruction offered by the relatively small collars or washers 20.

The various sections may be detachably secured to a building 21 by means of clamps 22 one of which is shown in detail in Fig. 4. Each of said clamps comprises a substantially semicircular portion, adapted to be screwed or otherwise secured to the building and provided with terminal hooks 22. After a section has been placed into its corresponding member 21 it may be securely but detachably held there by a wire 23 twisted at its opposite ends around said hooks 22.

The upper section 10 is shown connected to a roof gutter 24 to receive the discharge thereof and the lower section 15 is adapted to empty into any suitable drain. So long as the sections 10 to 15 are open the water or other liquid will flow from the gutter 24 down through the successive sections 10 to 15 and there will be no escape of liquid from the spout at any point in its length, including the joints between adjacent sections. If, however, any section should become clogged, either by the liquid freezing or due to collection of refuse or otherwise, the liquid will collect in that section until it reaches the clearance opening 17 immediately above, whence it will escape and flow

- to the outside of the spout. This is a marked advantage over prior spouts. Suppose that the lower spout 15 becomes clogged as by freezing. Instead of the liquid piling up in the spout and overflowing at the gutter 24 as would be the case in the ordinary spout, the downflowing liquid would escape at the clearance opening 17 between sections 14 and 15. Incidentally the loss of pipe due to bursting by freezing is minimized. Other advantages will now be obvious to those skilled in the art, in view of the foregoing disclosure, and such advantages need not be here enumerated.
- 15 The sections 10, 11, 12, etc., may be made of tinned or galvanized iron or other suitable material. The selection of the material best suited for the particular installation is a matter which is well within the skill of the average mechanic. Furthermore numerous modifications which do not depart from the scope of the invention as claimed hereinafter, will be suggested by the present disclosure. For example, instead of making 20 the sections of the shape shown in Figs. 1 to 3 they may each be made in the shape of hollow truncated cones, i. e., tapering in shape, as shown at 10^a, 11^b in Fig. 5.
- 25 In accordance with the provisions of the patent statutes, I have herein described the principle of operation of my invention, together with the apparatus, which I now consider to represent the best embodiment.

ment thereof, but I desire to have it understood that the apparatus shown is only illustrative and that the invention can be carried out by other means. Also, while it is designed to use the various features and elements in the combination and relation described, some of these may be altered, others omitted and some of the features of each modification embodied in the others without interfering with the more general results outlined and the invention extends to such use. 35

40 45 What I claim is—

1. A down spout comprising in combination, a plurality of serially connected identically shaped interchangeable pipe sections each of which extends into and discharges into the section below it, each of said sections being smaller at its lower end than its upper end to provide a clearance opening at each junction of said sections, each of said sections being provided at its lower end with a plurality of laterally extending pins and at its upper end with a plurality of slots in its side wall to receive the pins of the section immediately above. 50 55

2. The down spout set forth in claim 1 in which spacing devices are provided upon the pins. 60

In testimony whereof I hereto affix my signature.

JEAN MARTIAL LOBIT.
